UNITED STATES PATENT OFFICE

2,126,553

VACUUM PUMP

Carl S. Hornberger, Glen Ellyn, and Marshall N. States, Evanston, Ill., assignors to Central Scientific Company, a corporation of Illinois

Application April 26, 1935, Serial No. 18,364

15 Claims. (Cl. 230—207)

This invention relates to apparatus for producing high vacua, commonly called vacuum pumps, and the principal object is to increase the degree of exhaustion, or the height of the 5 vacuum and the speed of producing it.

Generally speaking, this is accomplished by connecting two eccentric pumps in series, the first, or finishing stage, being of large capacity and arranged to deliver past the other in the 10 initial operation, or until the pressure in the system is materially reduced, and then to deliver to the other that serves as a roughing stage, or fore pump, and by protecting the large finishing pump with a complete oil seal, and making the roughing 15 stage of sufficient capacity to really out-gas the oil in the sealing and lubricating system of the finishing stage, and thus prevent the oil necessary for lubrication and sealing from placing a limit on the finishing pump by releasing gas to 20 the chamber as the complete exhaust of the system is approached.

At atmospheric pressure lubricating oil contains dissolved air, absorbed gases, and volatiles which are released at lower pressures, and even a small 25 quantity of gas released to the pump chamber at extremely low pressure expands greatly and when regularly supplied by the necessary feed of oil, it slows down the exhaust and eventually determines the limit of vacuum that the apparatus can 30 produce. By practically out-gassing all the oil that goes into the sealing and lubricating system of the finishing stage that pump is left free to work on the system to be exhausted with all its capacity.

35 Further objects and advantages of the invention will appear as the disclosure proceeds and the description is read in connection with the accompanying drawings, in which

Fig. 1 is a perspective of the apparatus with 40 part of the casing at the right and the intermediate portion removed to reveal the interior;

Fig. 2 is an end elevation looking from the right in Fig. 1, with parts cut away on the line 2—2 of Fig. 3;

45 Fig. 3 is a plan section taken on the line 3—3 of Fig. 2;

Figs. 4, 5, 6 and 7 are sections taken on the lines 4—4, 5—5, 6—6 and 7—7, respectively, of Fig. 3;

Fig. 8 is a section taken on the line 8—8 of 50 Fig. 6;

Fig. 9 is a section on the line 9—9 of Fig. 3;

Figs. 10 and 11 are enlarged portions of Fig. 7;

Figs. 12, 13 and 14 are diagrammatic sectional views of the two pumps and their connections.

55 But these drawings and the corresponding spe-

cific description are used for the purpose of disclosure because they conform to an embodiment that has demonstrated its fitness for the purpose, and they are not intended to indicate the limits of the invention, which is susceptible of other 5 embodiments.

In the diagrams, Figs. 12, 13 and 14, sheet 4, the main pump, or finishing stage is indicated at A, and the fore pump, or roughing stage, is indicated at B.

10 The pump A comprises a casing 10 having a cylindrical pump chamber 11, having an intake port 12 and a vestibule chamber 13 connected with the chamber 11 by an exhaust port 14, the intake and exhaust being divided by a vane, or blade 15, 15 sliding in the casing and cooperating with the periphery of an eccentric rotor 16 that serves as a piston.

The pump B comprises a casing 17 having a cylindrical pump chamber 18, provided with an 20 intake port 19, an exhaust port 20, and between them is a vane, or blade 21, sliding in the casing and cooperating with the periphery of an eccentric rotor 22.

25 The pipe 23 leads from the vessel, or system, to be exhausted, and is connected with the pump casing by a fitting 24 which, together with the adjacent portion of the casing, provides a copious inlet passage leading to the intake port 12.

The vestibule chamber 13 is provided with a 30 ball check valve (several in a row) 25, by which the vestibule chamber may be exhausted to an exhaust chamber 26 open to the atmosphere at 27.

In these diagrammatic views 12 to 14, the 35 connection between the vestibule chamber and the intake of the pump B is indicated by a tube 28, and the exhaust port 20 of the pump B is shown connected with the exhaust chamber 26 by a tube 29. But this is for the purpose of simplifying the illustrations, and the actual connections are quite different.

A comparison of the successive positions shown 40 in Figs. 12 to 14 indicates the operation of the two pumps as the driving motor turns the large rotor 45 counterclockwise and the other rotor clockwise. In considering the difference in capacities apparent from these drawings, it will be seen that in the initial operation the fore pump B cannot handle all of the gas delivered by the finishing 50 pump A, and the pressure rises in the vestibule chamber 13 until the check valve 25 opens to discharge the contents directly into the chamber 26 until the delivery of the finishing stage A comes 55 within the capacity of the roughing stage B, 55

when the valve 25 will close and thereafter the pumps will work in series.

The casing 10 is made in several parts, but in the main is composed of end pieces 30 and 31 (Fig. 5 6) and an intermediate body piece 32 containing the cylindrical bore of the main pump chamber 11. The end piece 30 has a bearing 33 for the shaft 34, driven by the pulley 35, and equipped with two stuffing boxes 36 and 37. The end piece 31 also has a bearing (not shown) for the shaft 34 and a stuffing box 38, a portion of which appears in Fig. 6.

The vane, or blade 15 runs in a slot 39 in the body member 32 of the casing and is urged towards the rotor 16 by springs 40, Fig. 1, connected to the ends of a bar 41 (Fig. 6) on top of the blade and to the end pieces 30 and 31 by screws 42, near the lower ends of spring bores 43.

One wall 44 of the exhaust port 14 is inclined 20 towards the blade 15 (Fig. 1), and receives a tube 45, which serves as a valve cooperating with the inclined wall 44 and the adjacent surface of the blade to close the exhaust passage against re-entry of gas and the flow of oil from the vestibule chamber 13 after the fashion disclosed in the patent to Dubrovin, No. 1,890,571 of December 13, 1932, the ends of the tube being slightly reduced externally to admit a small amount of oil for lubrication and sealing.

30 In the ordinary operation of the pump there is no occasion for the valve 45 to open wider than in the position shown in Fig. 10, but when the pump has been standing for a long time and a large amount of oil has seeped into the pump chamber the first revolution of the rotor must discharge the bulk of that oil through the exhaust port. This makes it appropriate to provide for an emergency wide opening by permitting the valve to rise to the position shown in Fig. 11.

40 To achieve this the body member 32 of the casing is provided with a flat seat 46, which constitutes a retaining wall for the body of oil in the vestibule and upon which is secured angular keeper blocks 47 having spaces 48 (Fig. 6) between them to receive the teeth 49 on a bar 50 provided with a plurality of holes 51 for screws that compress springs 53 against the bar 50, and normally hold it in the position shown in Fig. 10, but upon being pressed from below by the valve 45, allow it to take the position shown in Fig. 11. 50 The gas discharged from the finishing pump passes through the spaces 48 into the vestibule. Likewise, oil in a thin layer flows over the seat or retaining wall 46 for supplying the cylinder 11 with lubricant. The oil at a depth below the surface cannot be entirely degassed because of hydrostatic pressure but the surface oil in the vestibule, being free of this pressure, is effectively degassed at low pressure and since the oil supplied to the cylinder is from the surface, the pump 55 is not handicapped by the adsorbed air contained in the oil and consequently, extreme low pressures have been obtained.

60 The wide slot in the body member 32 necessary to admit this valve mechanism is partially closed by a grating 54, made fast by machine screws 55 (Fig. 7) and having copious openings 56 to establish communication between the vestibule chamber 13 and the dome of an arched cover 57, secured to the top of the casing forming an extension of said chamber and affording working space for the blade 15.

65 The vestibule chamber 13 has an upright wall 58 and a substantially horizontal wall 59, the latter equipped with valve seats 60 (Figs. 9, 12, 75 13 and 14) to receive the ball valves 25.

The opening movement of those valves is limited by a stop 61 secured to the vertical wall 58 of the vestibule chamber (Fig. 3) by screws 62 passing through it and spacers 63.

The rush of the oil from the vestibule chamber during the initial operation of the pump is likely to reduce the level in the system below what is desirable and it is automatically returned through a float valve mechanism, as shown particularly in Figs. 3, 7 and 9. This float valve mechanism in like manner replenishes the oil gradually withdrawn from the vestibule chamber for lubricating and sealing the ports of the finishing pump. The wall 58 of the vestibule chamber is drilled and tapped at 64 to receive a valve plug 65, Fig. 9, having inlet openings 66 in a central passageway 67 leading through a valve seat 68 near the bottom. A lever 69 fulcrumed on a pin 70 in the forked end of the valve plug carries a valve stem 71 through a pin 72, and the lower end of the stem cooperates with the valve seat 68 to close the passageway when the lever is in the appropriate position, and open the passageway when the lever is raised above that position.

25 The control is by means of a float 73 at the free end of the lever, acted upon by the oil in the exhaust chamber, where the normal level is substantially as indicated in Fig. 9 by the line 74. In order to prevent the rush of oil from the adjacent valve displacing the float 73, the valve stop 61 (Fig. 3) is equipped with an angular plate 75, which serves as a shield or baffle.

30 The exhaust chamber 26 is also provided with a baffle 76 (Fig. 9) to prevent loss of oil through the exhaust outlet 27.

35 Incidentally, this baffle 76 (Fig. 9) is so placed in the exhaust chamber as to provide two paths of unequal length leading from valves 25 to the exhaust outlet 27. These paths are so related to the exhaust impulse of the pump that the noise 40 is damped, that is, one path is longer than the other whereby the crest of the impulse going around one end of the baffle will engage the trough, as it were, of that portion going around the other end whereby they tend to neutralize 45 each other thereby resulting in a quieter, smoother, flow of the exhaust air through the exhaust conduit 27.

40 The right end piece 31 of the casing is cored out to form a chamber 78 (Figs. 3, 5 and 6) provided with a door 79 (Figs. 1 and 5) to afford access to the shaft bearing, the stuffing box 38 and screws 42.

45 The end piece 31 is also cored out to provide a chamber 80 (Figs. 4 and 5), the end wall 81 of which is provided with a large opening closed by the plate 86 to permit the fore pump B to be inserted as a unit.

50 The pump B in this illustration is really two eccentric pumps in series, the casing of which includes the end plate 82 (Fig. 6) the cylinder rings 83 and 84, the intermediate plate 85, and the large end plate 86, the latter being bolted to the end wall 81 to secure the fore pump in place.

55 Two stage eccentric pumps of this general character are well known on the market, and may be had somewhat in the form shown by the patents to Dubrovin, No. 1,890,572 of Dec. 13, 1932 and to Klopsteg, No. 1,890,614 of Dec. 13, 1932.

60 The main pump shaft 34 projects through the end piece 31 and is equipped with a gear 87 (Fig. 1) meshing with a gear 88 on the shaft 89 of the fore pump B. The gears are enclosed by a cover 90 which also serves to enclose part of the pas- 70 75

sageway from the vestibule chamber 13 to the intake of the fore pump.

As shown, an opening 91 (Figs. 1 and 2) through the end wall 81 puts the upper portion 5 of the chamber 18 in communication with the inside of the cover 90, and an opening 98 (Figs. 2 and 6) puts the lower portion of the chamber 18 in communication with the inside of the cover 90.

10 The intake port 92 of the fore pump is through the end plate 86, the exhaust port from the first stage and the intake for the second stage is a bore 93 through the intermediate plate 85, and the exhaust port 94 (Figs. 4 and 6) of the second 15 stage leads into the chamber 80, which is in communication with the exhaust chamber 26 through a cored passage 85.

10 The end plates 30 and 31 are each provided with a groove 96 (Figs. 6 and 8) which has its 20 upper end in communication with the dome of the cover 57, which is in communication with the vestibule chamber through the openings 56 (Fig. 7). The other end 97 of each groove 96 is in communication with the vestibule chamber at the 25 end of the valve cylinder 45.

20 The grooves 96 at their lowermost portions are connected by a transverse bore 99 (Fig. 6) which also communicates with vertical bores 100 and 101, which establish communication with the 30 spring bores 43 and, hence, with the vestibule chamber.

25 The opening 91 (Figs. 1, 2 and 3) through the end wall 81 of the end piece 31 allows oil in the system to enter the chamber formed by that end 35 wall and the cover 90 enclosing the gearing, and the normal oil level in this chamber is about as indicated by the line 102 (Figs. 1 and 10) and is the same as that of the oil in the vestibule chamber 13 (Figs. 12, 13 and 14). The baffle 103 shields 40 the intake port 92 of the forepump and determines the maximum height of the oil level in the vestibule chamber 13 and chamber 18. When the oil level rises above the upper end of the plate 103, the oil will flow over the baffle and will 45 be drawn into the roughing pump and discharged into the chamber 80, which is in communication with the reservoir 26, on the discharge side of the roughing pump. The height of the oil in the chamber may be observed through the glass- 50 covered sight opening 111 (Fig. 6).

These various passages and grooves put oil in every joint of the pump casing to seal it, and all of the oil in the system for lubrication and sealing is in communication with the vestibule 55 chamber and subject to the pressure in that chamber. The fore pump, having its intake connected with the vestibule chamber in addition to exhausting it, serves to outgas all the oil in the system and, thereby prevent gas reaching the 60 chamber 11 of the finishing stage, either as an incident to lubrication, or as seepage through the joints of the casing.

The inlet ports 12 of the finishing stage and all passages leading to them are made very wide 65 as compared with their length to reduce the impediment to rarefied gas finding its way into the chamber of the finishing stage.

The main pump chamber 11 is $7\frac{1}{2}$ inches long and 8 inches inside diameter and the rotor 16 is 70 $6\frac{1}{2}$ inches outside diameter.

The cylindrical chambers of the fore pump are $2\frac{1}{2}$ inches inside diameter and 1 inch long, and the rotors are 2 inches in diameter.

The gear 87 has sixty teeth and the gear 88 75 seventy-two teeth, and 1 $\frac{1}{2}$ H. P. electric motor

is ample when geared down to drive the main shaft 34 at 450 R. P. M. which, with the ratio indicated would drive the fore pump shaft at 375 R. P. M.

With such a pump vacuum, less than one-hundredth of a micron has been produced with ten microns in the vestibule chamber.

The best mechanical pumps having similar volume heretofore available have reached a limit at 10 about one micron.

15 It frequently happens in the use of this apparatus that it is shut down, without being relieved, long enough for atmosphere to force oil from the exhaust chamber into the pump chambers of the roughing stage. Upon starting the motor with the apparatus in this condition the load is unduly heavy, and to relieve it, a friction clutch 104 (Figs. 1 and 6) is introduced into the gear 88 to allow the finishing stage to operate with comparative freedom while the oil in the 20 chambers of the roughing stage gradually works out through the restricted ports. As soon as the great resistance offered by the oil has been relieved, the clutch engages and the roughing stage begins to operate. This delayed operation of the 25 roughing stage is no detriment to the efficiency of the apparatus, for during the period that it is inactive, the finishing stage is working against comparatively high pressure, and is therefore delivering so much gas that the valves 25 are open 30 and the operation of the roughing stage would be to no effect.

35 The stuffing boxes 36 and 37 are of the ring seal type shown and described in Dubrovin, No. 1,890,573, Dec. 13, 1932; and the box 37 is connected by a pipe 105 (Figs. 6 and 9) with the vestibule chamber 26 below the oil level. Hence, any leakage past the box is degassed oil.

The fitting 24 (Fig. 1) has a wide flange 106 fitted to a machined face 107 on the body piece 40 32 of the pump casing 10; and the flange is provided with a sealing groove 108 connected by a drilled passage 109 (Fig. 8) through the body piece with sealing groove 96. As a result, any leakage, upon reaching the groove, passes to the 45 vestibule and is taken off by the fore pump.

We claim as our invention:—

1. In apparatus for producing high vacua, a pump of large capacity having a pump chamber and an exhaust vestibule chamber, a check valve 50 permitting gas to flow from the pump chamber to the vestibule, an oil seal for the pump chamber connected with the vestibule and subject to the pressure in the vestibule, a second pump having its inlet connected with the vestibule 55 chamber and of small capacity relative to the first pump, but of sufficient capacity to outgas the oil in the seal and vestibule, a check valve permitting exhaust from the vestibule when the delivery of the first pump exceeds the capacity 60 of the second pump, an exhaust chamber receiving the exhaust from the vestibule chamber, a return passage connecting the exhaust and the vestibule chamber, a valve controlling the return passage, a lever for operating the valve, and a 65 float for the lever.

2. A pump comprising a casing having a pump chamber, a vestibule chamber normally at sub-atmospheric pressure and an exhaust chamber having sealing oil therein, a rotor in the pump 70 chamber, a check valve between the pump chamber and the vestibule chamber, another check valve between the vestibule chamber and the exhaust chamber, a second pump chamber, an intake passage for said second pump chamber in 75

- communication with said vestibule chamber, an oil seal for the first pump supplied solely from the vestibule chamber and means including valve mechanism to return oil to the vestibule chamber
- 5 when oil in the exhaust chamber reaches a selected level.
3. A pump comprising a casing having a pump chamber, a vestibule chamber and an exhaust chamber, a rotor in the pump chamber, a check valve between the pump chamber and the vestibule chamber, another check valve between the vestibule chamber and the exhaust chamber, an oil seal for the pump supplied from the vestibule chamber, means including valve mechanism for returning oil to the vestibule chamber when oil in the exhaust chamber reaches a selected level, a second pump having an intake connected with the vestibule chamber and an exhaust connected with the exhaust chamber.
- 20 4. In a vacuum pump mechanism, a finishing pump having a rotary piston and intake and discharge passages, a two-stage roughing pump, a chamber for containing oil for supplying the same to said finishing pump only, for sealing and lubricating the same, a shallow mass of oil in said chamber, one of said passages being in communication with said chamber beneath, but adjacent to, the surface of said oil, the intake passage of said roughing pump being in communication with said chamber above the level of said oil whereby said oil will be degassed prior to the entry into said finishing pump, a reservoir in the discharge passage of said roughing pump for collecting oil contained in the discharge gases of said pump, and float controlled valve means for supplying oil from said discharge passage to said chamber when the oil in said last-named passage rises above a predetermined level.
- 45 5. In a vacuum pump, a cylinder, a piston for said cylinder, intake and discharge passages for the pump, valves in the discharge passage, and a baffle in the discharge passage so positioned relative to said valves as to cause the discharge gas to strike said baffle at right angles thereto closer to one end of said baffle than to the other whereby said gas is caused to take two paths of unequal lengths, whereby the noise incident to the operation of said pump will be reduced to a minimum.
6. In a vacuum pump, a finishing pump, a roughing stage pump, a chamber for containing a small amount of oil for lubricating said pumps, an exhaust port for said finishing pump opening into said chamber and constituting the principal means for conducting oil from said reservoir to said finishing pump for lubricating the same, an intake passage for said roughing pump in communication with said chamber above the level of the oil therein, a discharge passage for said roughing pump, a reservoir in said discharge passage, a passage between said chamber and reservoir, and a float valve for controlling the passage of oil from said reservoir into said chamber.
- 65 7. In a vacuum pump, a casing having a finishing pump therein, an oil chamber for receiving the discharge from said pump, an end piece for said casing, said end piece having a chamber therein, the outer wall of said chamber having an opening therethrough, a closure plate for said opening, a roughing pump secured to said closure and insertable through said opening, and an intake for said roughing pump in communication with said oil chamber.
8. An apparatus for producing high vacua comprising a finishing pump having a cylinder, a piston movable in said cylinder, an intake passage
- for said cylinder and an exhaust vestibule for containing oil for lubricating said cylinder and into which said pump exhausts, a check valve in said vestibule at the level of said oil, said valve arranged for admitting oil to said cylinder from the surface only of said oil in a thin layer for lubricating the cylinder, a roughing pump, and a passage connecting the intake of the roughing pump with said vestibule above the level of the oil therein whereby the amount of oil supplied to said cylinder is degassed.
9. An apparatus for producing high vacua comprising a finishing pump having a cylinder, an intake for said cylinder, a piston movable in said cylinder and an exhaust vestibule for containing oil for lubricating said cylinder and into which said pump exhausts, a check valve in said vestibule, a valve seat for said check valve, a retainer wall associated with said seat, said wall constituting retaining means for said oil whereby oil supplied to said cylinder flows over said wall from the surface of the oil in said vestibule, a two stage roughing pump in series having intake and discharge passages, and a passage connecting the intake of said roughing pump with said vestibule above the level of the oil therein, whereby the oil in said vestibule will be under partial vacuum for degassing the oil supplied to said cylinder.
- 10 10. An apparatus for producing high vacua comprising a finishing pump having a cylinder, intake and discharge passages for said cylinder, a piston movable in said cylinder, a roughing pump in series with said finishing pump and having intake and discharge passages, a reservoir for containing a mass of oil for lubricating said cylinder, means for maintaining the oil in said reservoir at a pressure not substantially above that of the intake of said roughing pump for degassing said oil, and a passage in communication with said reservoir at substantially the oil level therein for conducting degassed oil from the surface of said mass to said cylinder for lubricating the same.
11. An apparatus for producing high vacua comprising a finishing pump of large capacity, a roughing pump of small capacity, a discharge passage comprising a vestibule containing oil for said finishing pump in communication with the intake of said roughing pump, an oil sealed relief check valve in a wall of said vestibule for permitting the escape of the exhaust through said passage from said finishing pump only when the delivery of the finishing pump exceeds the capacity of said roughing pump.
12. In apparatus for producing high vacua, a pump of large capacity having a pump chamber, an intake passage for said chamber, and an exhaust vestibule, said vestibule being adapted to contain oil for lubricating said pump, a check valve permitting gas to flow from the pump chamber to the vestibule, an oil seal for the pump chamber connected with the vestibule and subject to the pressure in the vestibule, a second pump having intake and discharge passages, said last-named intake passage connected with the vestibule above the level of the oil therein and of small capacity relative to the first pump, but of sufficient capacity to outgas the oil in the seal and vestibule, a check valve permitting exhaust to be discharged from the vestibule independently of the second pump when the delivery of the first pump exceeds the capacity of the second pump, and an oil seal for said last-named valve.

13. A high vacuum pump comprising a finishing pump, an intake and a discharge port for said finishing pump, an oil reservoir for receiving the discharge from the discharge port of said finishing pump, a valve for said port, oil within said reservoir at substantially the level of said valve and arranged to escape from the surface thereof past said valve into the discharge side only of said finishing pump for lubricating the latter, a roughing stage pump provided with an intake passage and a discharge passage and having its intake passage in communication with said reservoir above the oil level therein whereby oil supplied to said finishing pump will be out-gassed by said roughing pump.
14. In a vacuum pump, a finishing pump, a roughing stage pump, intake and discharge passages for said pumps, a chamber having its major portion above said finishing pump for containing a shallow body of oil for lubricating said finishing pump by gravity, the discharge passage for said finishing pump opening into said chamber through which finishing pump discharge passage oil is supplied to the finishing pump, the intake passage for said roughing pump being in communication with said chamber above the level of the oil therein for outgassing the oil in said chamber, a reservoir in the discharge passage of said roughing pump, a passage between said chamber and reservoir, and a float valve for controlling the passage of oil from said reservoir into said chamber.
15. In a high vacuum pump, a rotary finishing pump of large capacity, a rotary two-stage roughing pump of smaller capacity arranged in series, a vestibule chamber for receiving the discharge from said finishing pump, an oil retaining wall in said vestibule for forming a chamber for containing oil for lubricating said finishing pump by supplying the same directly to the discharge side of said finishing pump in a thin layer over said wall, and means for connecting the intake of said roughing pump to said chamber above said wall and the level of the oil in said chamber for degassing all of the oil supplied to the discharge side of the finishing pump.
